(57) **CLAIM**

The ornamental design for a sound bar mount, as shown and described.

DESCRIPTION

FIG. 1 is a perspective view of a sound bar mount showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the drawings represent portions of the sound bar mount that form no part of the claimed design.

The claim is directed to the collective appearance of the sound bar mount shown in FIGS. 1-8.
